UNITED STATES PATENT OFFICE.

WILLIAM L. IWAN, OF STREATOR, ILLINOIS.

PIPE-HANGER.

No. 911,877.

Specification of Letters Patent.

Patented Feb. 9, 1909.

Application filed August 23, 1906. Serial No. 331,723.

To all whom it may concern:

Be it known that I, WILLIAM L. IWAN, a citizen of the United States, residing at Streator, in the county of LaSalle and State of Illinois, have invented a new and useful Improvement in Pipe-Hangers, of which the following is a specification.

My invention relates particularly to means for fastening pipes to walls; and my primary object is to provide a device for the purpose indicated which can be cheaply manufactured, and which is perfectly adapted to its purpose.

The invention is illustrated in the accompanying drawing, in which—

Figure 1 represents a perspective view of a corner of a building having a pipe secured to a wall thereof by means of my improved pipe-hangers; Fig. 2, a perspective view of one of the hangers; and Fig. 3, a section taken as indicated at line 3 of Fig. 2.

A represents a building wall; B a pipe; and C, my improved pipe-hanger. The hanger C comprises a tapering shank c, and curved pipe-engaging portion c¹ carried thereby.

The device is stamped from sheet-metal or bar-metal, and the portion c¹ is then bent in the plane of the metal, *i. e.*, edgewise, from the condition indicated by dotted lines in Fig. 2 to the condition indicated in full lines in said figure. The part c¹ tapers somewhat at its free extremity, as shown.

At the junction of the portion c¹ with the shank c, an offset c² is formed on one edge of the device, affording a head having a shoulder c³ which may be struck by a hammer in driving the device into a wall. Near the base of the shank c, the metal is struck laterally to form a wedge-shaped boss c⁴. This boss enters as a wedge when the shank is driven into a wall, and aids in stiffening the hanger against lateral play. It serves, also, to mark the depth to which the shank should be driven. The shoulder c³ serves to receive the blows of a hammer in driving the hanger into the wall. Hangers of the improved construction may be economically cut from sheet-metal, or bar-metal, without waste of material, and are very strong and durable.

What I regard as new, and wish to secure by Letters Patent, is—

A pipe-hanger formed of sheet-metal, having a tapering shank and a portion curved edgewise of the metal and forming a pipe-engaging portion, the hanger having also a laterally struck wedge-shaped boss at the base of the shank and an offset shoulder at the base of the convex edge of the curved portion, for the purpose set forth.

WILLIAM L. IWAN.

In the presence of—

J. H. LANDES,
C. W. WASHBURN.
